RADIO FREQUENCY TUBE WITH LOW INTERNAL IMPEDANCE

Carl H. Scullin, Florham Park, N. J., assignor to Westinghouse Electric Corporation, East Pittsburgh, Pa., a corporation of Pennsylvania

Application December 29, 1951, Serial No. 264,027

3 Claims. (Cl. 313—308)

1

My invention relates to electrical discharge tubes and in particular relates to a novel control-electrode arrangement for electrical discharge tubes of the high-vacuum type. It is particularly useful for high power oscillation generators or amplifiers of higher radio frequencies.

For many fields of radio frequency power service, it is desirable to have a generator or amplifier of low internal impedance; that is to say, an electronic tube capable of operating at a relatively low plate voltage and high plate current. Such a low impedance source is much easier to match with the load impedances ordinarily encountered in both radio broadcasting and radio frequency heating than are high impedance sources. A low impedance tube likewise makes it possible to use a cheaper and simpler modulation transformer, and facilitates the attainment of wide bandwidth in television service.

One object of my invention is to provide a grid-controlled electron tube which shall have a low anode-to-cathode impedance.

Another object of my invention is to provide a novel type of grid-controlled electron tube.

Still another object of my invention is to provide an electrical discharge tube with a novel type of control electrode.

Yet another object is to provide a novel type of amplifier.

A further object is to provide a grid-controlled tube in which an unusually small fraction of the electron-emission of the cathode finds its way to the control-electrode during the time of electron conduction to the anode.

A still further object is to provide a grid-controlled electrical discharge tube in which the control-voltage needed for effective operation is unusually low.

Yet another object is to provide a grid-controlled electron tube in which the ratio of anode-to-cathode impedance to anode-to-cathode capacitance is lower than in conventional tubes of the present art.

A still further object is to provide an electron tube having a control electrode in which secondary emission from the electrodes is minimized.

Other objects of my invention will become apparent to those skilled in the art upon reading the following specification taken in connection with the drawings, in which:

Fig. 1 is a view in sectional elevation of an electron tube embodying my invention, taken on line I—I of Fig. 2.

Fig. 2 is a view in section along the plane II—II of Fig. 1.

2

Fig. 3 is a graph showing curves of voltage and current under one condition of use of a tube embodying the invention.

Referring in detail to Fig. 1, an electron tube embodying my invention comprises a vacuum-tight container 1 having a cylindrical metallic wall-portion 2 which forms its anode, and a glass base-portion 3 sealed thereto. An annular ring 4 of material, such as described in Patent No. 2,062,335 sold under the trade-mark "Kovar," is brazed to the lower edge of the anode 2, and an annular component 5 of the glass base-portion 3 is sealed to ring 4. A second annular "Kovar" ring 6 has the lower edge of the glass member 5 and the upper edge of a glass bowl 7 sealed to it. The base-portion of the bowl 7 has a "Kovar" ring 8 sealed through it, and also a center-post 9 which projects along the axis of anode 2 nearly to the closed upper end thereof.

The center-post 9 has fastened to it an insulating disc 11 provided with a downward-projecting hub. On the upper face of disc 11 is supported a metal disc 12 from equally-spaced points on the periphery of which there project a plurality of fingers 13. Adjacent the lower face of disc 11 is a metal disc 14 which is centered about center-post 9 by the insulating hub of disc 11, and which is electrically connected to ring 8 by members 15. Half way between posts 13 there project upward a set of posts 16 which pass through insulating openings in disc 12, and through disc 11 to anchor in disc 14. A suitable spring-member 17 slidably surrounds center-post 9 and its upper end biases upward a sleeve 18 which is slidable on center-post 9. The upper end of sleeve 18 engages an insulating collar 19, which slidably engages the upper portion of center-post 9, and which supports a plate 21.

The ring 6 is provided with three projecting arms 22 at 120 degree intervals which support a control-electrode 23 having the form of a cylinder coaxial with the anode 2.

As is shown more clearly in Fig. 2, the control electrode 23 is a tube of high-melting metal, such as molybdenum, having longitudinal grooves 24, one for each vertical strand 25 of the cathode filament. The grooves 24 are preferably spaced away from the filament 25 by the minimum distance which will withstand the potential during the positive phase of voltage impressed between the control-electrode and cathode, and which will provide sufficient mechanical clearance during operation of the tube, allowing also for expansion of the cathode when heated to its operating temperature. To give a specific example, the tube

may have an .018" diameter filament wire with a clearance between filament wire and control electrode slot of .005" on each side. This geometry will result in an estimated control electrode current density of 4 amp./cm.² at a positive instantaneous control voltage of about 40 volts. This current density is greater than can be supplied by most practical cathodes, thus the control electrode would be successfully robbing the anode of virtually all current. The anode 2 may be spaced about $\frac{1}{8}$ " from the surface of the control electrode 23, its minimum instantaneous potential, at the time of maximum anode current flow, being about 800 volts positive where it would draw about 500 ma. cm.² from the cathode. The control electrode would be negative at this instant and thus draw no current.

The strands 25 of the cathode are all supported at their upper ends from posts 26 projecting downward from the disc 21. The lower ends of alternate filaments 25 are respectively attached to the fingers 13 set in disc 12 and fingers 16 set in disc 14 as already described. A heating-current supply for the cathode is connected between cylinder 8 and center-post 9. Thus heating current for the cathode flows from center-post 9 into disc 12, thence up fingers 13 to, let us say, the odd numbered filaments 25 and disc 21, then down the even-numbered filaments 25 to fingers 16 and disc 14, and member 15 to cylinder 8. The spring 11 exerting upward bias on disc 21 holds all the filaments 25 taught and straight in the grooves 24.

With an electrode structure such as I have described and an anode potential of over 1000 volts positive to the cathode, a positive control electrode voltage of 40 volts will cause nearly all of the electrons emitted by the cathode strand 25 to strike the control electrode 23, thus effectively cutting off all current flow from the cathode to the anode. Nevertheless, the small spacing of the control-electrode from the cathode makes a relatively small control voltage effective and the power input to the control-electrode is still relatively small.

Reduction of the positive control-electrode voltage to zero or a small negative value suffices however to cause substantially all the electrons emitted by the cathode to flow to the anode. Since there is no control-electrode structure actually positioned between the cathode strand and the anode, the current flow between the two approaches the conditions present in a diode, and the voltage drop from anode to cathode remains low, thus giving a tube of high perveance, i. e., a low anode-to-cathode resistance.

Such a tube is particularly advantageous for use in a class "C" amplifier, where the control-

electrode is operated with a positive bias. Fig. 3 indicates the operation under such conditions, curve e_p representing the anode voltage alternating about a D. C. plate-bias E_b . The control-electrode voltage e_g alternates about a positive grid-bias E_c and, unlike conventional class "C" amplifier operation, in phase with the plate voltage e_p . The curve i_p shows the plate current, which flows during the negative half-cycle of the plate alternating voltage.

I claim:

1. An electrical discharge device comprising a cylindrical anode, a cathode constituted by a plurality of strands in a circular series coaxial with said cylindrical anode and inward therefrom, and a control electrode having portions thereof interposed between said strands whereby said electrode provides a plurality of parallel grooves each containing one of said strands, and each of said strands having a clearance from the said electrode portions that form the groove therefor less than the diameter of the strand.

2. An electrical discharge device comprising a cylindrical anode, a cathode constituted by a plurality of strands in a circular series coaxial with said cylindrical anode and inward therefrom, and a control electrode having radial portions thereof interposed between said strands whereby said electrode provides a plurality of parallel grooves each containing one of said strands, and each of said strands having a diameter more than half of the width of the groove containing the strand.

3. An electrical discharge device comprising a cylindrical anode, a cathode constituted by a plurality of strands in a circular series coaxial with and inward of said cylindrical anode, and a coaxial control electrode having a plurality of parallel grooves therein parallel to the axis of said anode and electrode, each groove having a strand of said circular series of strands therein, and said groove having a width greater than the diameter of the strand therein and affording a clearance between the strand and each side of the groove in the range between one third and one quarter of the strand diameter.
